UNITED STATES PATENT OFFICE.

RALPH STUDDARD, OF DOUBLE SPRINGS, ALABAMA.

ATTACHMENT FOR CARBURETERS.

1,282,650.

Specification of Letters Patent. Patented Oct. 22, 1918.

Application filed May 4, 1917. Serial No. 166,433.

To all whom it may concern:

Be it known that I, RALPH STUDDARD, a citizen of the United States of America, residing at Double Springs, in the county of 5 Winston and State of Alabama, have invented certain new and useful Improvements in Attachments for Carbureters, of which the following is a specification, reference being had therein to the accompanying 10 drawing.

This invention relates to carbureters and has for its object the production of a simple and efficient fuel attachment adapted to be used in connection with carbureters and the 15 like whereby oil or kerosene may be used in producing an efficient explosive medium in place of gasoline.

Another object of this invention is the production of a simple and efficient means 20 for gasifying oil or kerosene as the same passes through the carbureter and to the intake manifold.

With these and other objects in view this invention consists of certain novel combinations, constructions and arrangements of 25 parts as will be hereinafter fully described and claimed.

In the drawings:

Figure 1 is a side elevation being partly 30 shown diagrammatic, showing the arrangement of the several pipes leading to the carbureter and intake and exhaust manifolds;

Fig. 2 is a vertical section through the main 35 valve casing for controlling the admission of kerosene and oil to the carbureter;

Fig. 3 is an enlarged section taken on the line 3—3 of Fig. 1, looking in the direction of the arrow.

Fig. 4 is a vertical section through the 40 suction pump used in connection with the present invention;

Fig. 5 is a section taken on the line 5—5 of Fig. 1;

Fig. 6 is a section taken on the line 6—6 45 of Fig. 1;

Fig. 7 is a plan view of the operating lever and support which controls the opening and closing of the main control valve.

By referring to the drawings it will be seen 50 that 1 designates the casing of the main control valve within which casing 1 is mounted an elongated tapering rotary valve 2 as clearly illustrated in Fig. 2 of the drawing. This casing 1 is provided with a kerosene or fuel passage 3, a heated air passage 4

and a water passage 5 extending transversely therethrough. A pipe 6 is connected to and communicates with the kerosene or fuel passage 3 and is adapted to fit to the carbureter 7 as will be clearly understood by carefully 60 considering Fig. 1 of the drawings. The pipe 10 is also connected to the valve casing 1 and communicates with the water passage 5 for conveying water to the intake manifold 11 as is also clearly illustrated in 65 Fig. 1 of the drawings. It should be understood that the heated air pipe 8 will convey exhaust gases from the exhaust manifold 9 through the passage 4 and these exhaust gases will be discharged out through the 70 discharge pipe 12 and from this pipe into a muffler 13 of any suitable or desired construction. The heated air pipe 8 is adapted to fit somewhat closely in engagement with the pipes 6 and 10 for the purpose of heating 75 these pipes 6 and 10 and thereby adding to the gasification of the kerosene or fuel which passes through the pipe 6 and also assisting in heating the air passing through the pipe 10. The valve 2 is of course provided with suitable registering apertures or 80 ports 14 for forming a communication and constituting a continuous passage through the passage ways 3, 4 and 5 as illustrated clearly in Fig. 2 of the drawings.

The water supply pipe 10 carries a nozzle 15 at its upper end and this nozzle 15 is provided with a forwardly projecting threaded end 16 which is formed into the intake carbureter 11 as shown in detail in Fig. 6 for 90 the purpose of discharging or injecting water into the intake manifold 11 as the fuel passes therethrough. The nozzle 15 is of course provided with a suitable passage way or port 17 to permit the free passage of 95 steam or water therethrough. A needle valve 18 is adjustably supported within the nozzle 15 and is adapted to regulate the size of the discharge opening 19 formed in the discharge end of the nozzle 15. A suitable 100 head 20 is formed upon the outer end of the needle valve 18 for facilitating the operation of the needle valve and the proper positioning thereof. A suitable packing 21 is carried by the nozzle 15 and fits snugly 105 around the needle valve 18 to prevent leakage therethrough. It of course, should be understood that suitable unions or packings are formed around the junctions of all of the pipes used in connection with the present de- 110

vice in order that a proper seal may be produced at such junctures.

As shown in detail in Fig. 5 and as also indicated in Fig. 1, an elbow 22 is connected to the exhaust manifold 9 by being threaded therein and this elbow 22 carries a packing 23 to which the heated air pipe 8 is connected for the purpose of permitting the exhaust gases to be readily and conveniently conveyed from the exhaust manifold 9 and through the pipe 8 to the muffler 13.

The carbureter 7 is directly connected to the intake manifold 11 as shown in Fig. 1 and the carbureter 7 also carries a heating supply pipe 24 which heating supply pipe 24 is connected by means of a T-joint 25 to the outer end of the exhaust manifold 9 thereby conveying heated air to the carbureter 7 for the purpose of maintaining the proper temperature within the carbureter.

The casing 1 is provided with a gasolene intake passage 26, which gasolene intake passage 26 communicates with a vertically extending passage 27, the passage 27 also communicating with the discharge end of the passage 3 before described. A suitable port 28 is formed in the rotary valve 2 and this port extends at an angle to the ports 14 previously described in order to prevent the passage of gasolene into the passage way 3 while the passage ways 14 communicate with the passage ways 3, 4 and 5. A suitable gasolene supply pipe 29 is connected to the casing 1 and communicates with the passage way 26 and this pipe 29 is connected to a gasolene supply tank 30 illustrated in Fig. 1. The casing 1 is provided with a vertically extending entrance opening 31 which is normally closed by means of a plug 32. It should be understood that the vertically extending passage 27 may be readily cleaned by the removal of this plug should the passage become clogged.

The rotary valve 2 is provided with a reduced lower end 33 upon which is mounted a coiled spring 34 for the purpose of maintaining the rotary valve 2 snugly within the casing 1. This valve 2 is provided with a socket 35 at the upper end thereof within which socket 35 is mounted a head 36 held firmly therein by means of locking screws 37. An operating rod 38 is universally connected to this head 36 and this rod 38 is in turn connected to the operating handle 39. This operating handle 39 is pivotally mounted upon a gage plate 40 which gage plate is provided with suitable legends thereon for permitting the operator to determine the proper position of the rotary valve 2 within the casing 1. When the operating lever 39 is swung toward the right so as to overhang the legend reading 65 "water, air or kerosene", the kerosene and

water will pass through the valve 2 and through the proper pipes, the kerosene passing to the carbureter and the water to the intake manifold as will be obvious by carefully considering Fig. 1. When the operating lever 39 is swung toward the left to overhang the legend "gasolene", all of the ports in the valve 2 will be closed to the respective passage ways formed in the casing 1 with the exception of the port 28 which will open the passage way 26 and permit the flow of gasoline from the pipe 29 down through the passage way 27 and out through the pipe 6 to the carbureter. There is still another legend placed in the center of the gage plate 40 which is entitled "pump" and by swinging the lever 39 to a central position the port 41 at the lower end of the valve 2 will be thrown to such position as to form a communication and a continuous passage through the passage way 42 formed in the bottom of the casing 1. This passage way 42 communicates with the bottom of the carbureter 7 by means of a suction pipe 43 and the opposite end of the passage 42 communicates with the bottom of the suction pump 44 by means of a pipe 45.

The upper end of the pipe 45 engages a valve casing 46 within which valve casing is mounted a spring pressed ball valve 47 which is adapted to normally remain in a closed position. The casing 46 is connected directly to the bottom of the pump casing 44 and a discharge valve casing 48 is connected to the side of the pump casing 44 as shown in Fig. 4 of the drawings. The spring pressed ball valve 49 is carried by the casing 48 and is adapted to normally remain in a closed position and prevent the passage of liquid through the casing 49 into the pump casing 44. A discharge pipe 50 is connected to the casing 48 and is in turn connected to the top of the kerosene supply tank 51 shown clearly in Fig. 1 of the drawings.

The passage way 5 formed in the casing 1 is connected at its outer end with a pipe 52 which pipe 52 communicates with a water supply tank 53, which tank may be placed in any suitable or convenient position provided the same is not placed above the discharge end of the pipe 10 or in fact above the nozzle 15. The suction maintained within the intake manifold 11 will be sufficient to draw sufficient water for proper mixture into the intake manifold 11.

The operation of the device is as follows: In the usual starting of the engine it may be preferable to admit gasolene into the carbureter in order that a proper mixture of fuel may be obtained. The operating lever 39 is then swung to the position for closing all of the ports in the rotary valve 2 with the exception of the port 28. This will admit the flow of gasoline from the tank 18

30 through the pipe 29 through the casing 1 to the pipe 6 and into the carbureter 7 and from the carbureter 7 through the intake manifold 11 to the cylinders of the engine.

5 When it is desired to cut off the supply of gasoline the lever 39 is then swung toward the left as shown in Fig. 7 thereby closing the port 28 and opening the ports 14 of the valve 2. This will permit the passage of 10 kerosene from the tank 51 through the pipes 6 and casing 1 and intake carbureter 7. At the same time water will pass from the tank 53 through the pipe 52, casing 1, pipe 10 and be injected into the intake manifold 11 15 through the nozzle 15. At the same time heated air or exhaust gases will pass through the pipe 8 from the elbow 22 and exhaust manifold 9 through the casing 1 and passage way 4 through the pipe 12 and out through the muffler 13. When it is again desired to 20 admit gasoline into the carbureter 17 the lever 39 is swung to a central or neutral position thereby closing all of the ports with the exception of the port 41 of the rotary 25 valve 2. The pump 44 may then be operated by reciprocating the plunger 54 within the casing 44. This will draw the kerosene from the carbureter 7 due to the fact that the pipe 45 is connected to the bottom of the 30 carbureter 7 and draw the kerosene into the casing 44. Upon the return stroke of the plunger 54 the kerosene will be forced out through the valve casing 48 and into the kerosene reservoir 51 through the pipe 50. 35 The lever 39 may then again be thrown toward the left for the purpose of pumping gasoline to the carbureter.

From the foregoing description it will be seen that a very simple and efficient means 40 has been produced for permitting the use of kerosene or similar fuel in connection with explosive engines and the like and at the same time producing an efficient explosive medium for admitting the same to the 45 cylinders of the engine.

It should be understood that in actual use the pipes 6, 8 and 10 may be wrapped together for the purpose of retaining as much heat as possible but it is thought unnecessary to show this wrapping for the 50 reason that it is common to connect or wrap pipes for the purpose of retaining the heat units. However it is important that the pipes 6, 8 and 10 should be arranged in close 55 proximity to each other in order that the greatest amount of efficiency may be obtained. It is of course understood that the usual needle valve 55 is carried by the carbureter 7.

60 By carefully considering Fig. 2 of the drawings, it will be seen that a plurality of apertures 14' are formed in the casing 1 for the purpose of permitting bolts or other securing means to pass therethrough, thereby 65 permitting the casing 1 to be efficiently

supported upon or attached to the motor of an automobile or the like.

What is claimed is:—

1. The combination with an exhaust manifold, a carbureter, of a control casing, a valve mounted within said control casing, said control casing provided with passage ways formed therein, said valve provided with ports adapted to communicate with the passage ways in said casing at will, a pipe 70 connected to one of said passage ways and communicating with said carbureter for supplying fuel to said carbureter, a second pipe connected to the exhaust manifold of an engine and communicating with one of said 75 passage ways, means connected to the last mentioned passage way for conveying exhaust gases from said casing, the exhaust gases passing through said pipe being adapted to heat the fuel passing through first 80 mentioned pipe, a third pipe connected to said intake manifold and communicating with one of said passage ways for injecting water into said intake manifold, said exhaust pipe being adapted to also heat said 85 water pipe, and a fourth pipe connected to the bottom of said carbureter and also connected to said control casing and adapted to suck fuel from said carbureter at will.

2. The combination with an exhaust manifold, a carbureter, of a control casing, a valve mounted within said control casing, said control casing provided with passage ways formed therein, said valve provided with ports adapted to communicate with the 100 passage ways in said casing at will, a pipe connected to one of said passage ways and communicating with said carbureter for supplying fuel to said carbureter, a second pipe connected to the exhaust manifold of an engine and communicating with one of said 105 passage ways, means connected to the last mentioned passage way for conveying exhaust gases from said casing, the exhaust gases passing through said pipe being adapted to heat the fuel passing through first 110 mentioned pipe, a third pipe connected to said intake manifold and communicating with one of said passage ways for injecting water into said intake manifold, said exhaust pipe being adapted to also heat said water pipe, and a fourth pipe connected to the bottom of said carbureter and also connected to said control casing and adapted to suck fuel from said carbureter at will and 115 means connected to said last mentioned pipe for sucking fuel from said carbureter and returning the same to its original source.

3. The combination with an exhaust manifold, a carbureter, of a control casing, a valve mounted within said control casing, said control casing provided with passage ways formed therein, said valve provided with ports adapted to communicate with the 125 passage ways in said casing at will, a pipe 130

connected to one of said passage ways and communicating with said carbureter for supplying fuel to said carbureter, a second pipe connected to the exhaust manifold of an engine and communicating with one of said passage ways, means connected to the last mentioned passage way for conveying exhaust gases from said casing, the exhaust gases passing through said pipe being adapted to heat the fuel passing through first mentioned pipe, a third pipe connected to said intake manifold and communicating with one of said passage ways for injecting water into said intake manifold, said exhaust pipe being adapted to also heat said water pipe, a fourth pipe connected to the bottom of said carbureter and also connected to said control casing and adapted to suck fuel from said carbureter at will, and a pump connected to said last mentioned pipe, a fuel reservoir communicating with said casing, and means connected to said fuel reservoir and also connected to said pump

for facilitating the return of fuel from said carbureter to said reservoir.

4. In combination with an exhaust manifold, an intake manifold, a carbureter, means for supplying heated air to said carbureter from said exhaust manifold, a control casing, pipes for supplying fuel to said carbureter and injecting water into said intake manifold, a pipe for conveying exhaust gases from said exhaust manifold passing in close proximity to said fuel pipe and water supply pipe, means for controlling the opening and closing of the passages through said control casing, reservoirs placed adjacent said control casing, and pipes connected to said reservoirs and communicating with passage ways formed in said control casing for admitting fuel and water through said control casing.

In testimony whereof I hereunto affix my signature.

RALPH STUDDARD.
